(57) **CLAIM**

The ornamental design for an wearable device electronic display with graphical user interface, as shown and described.

DESCRIPTION

FIG. 1 is a front view of an wearable device electronic display with graphical user interface, showing our new design; and,

FIG. 2 is a front view of a second embodiment thereof. The broken line showing of the electronic display forms no part of the claimed design. The broken line showing of the hour, minute and second hands, and text forms no part of the claimed design.
